DESIGN FOR A COMBINED FOLDING TOOTH- BRUSH AND RECEPTACLE THEREFOR

Ted R. Stacey, Chicago, Ill., assignor to Gem Die
& Mold Company, Chicago, Ill., a corporation
of Illinois

Application August 9, 1947, Serial No. 140,791

Term of patent 14 years

(Cl. D9—2)

To all whom it may concern:

Be it known that I, Ted R. Stacey, a citizen of the United States, residing at Chicago, in the county of Cook and State of Illinois, have invented a new, original, and ornamental Design for Combined Folding Toothbrush and Receptacle Therefor, of which the following is a specification, reference being had to the accompanying drawing, forming a part thereof.

Figure 1 is a side elevational view of a combined folding toothbrush and receptacle therefor with the receptacle and toothbrush in assembled position, embodying my new design;

Fig. 2 is an end elevational view thereof;

Fig. 3 is an elevation viewed from the opposite end thereof;

Fig. 4 is a plan view thereof; and

Fig. 5 is a perspective view thereof showing

the receptacle and toothbrush in disassembled position.

I claim:

The ornamental design for a combined folding toothbrush and receptacle therefor, substantially as shown.

TED R. STACEY.
